UNITED STATES PATENT OFFICE.

HJALMAR NILSSON, OF HAMMOND, INDIANA.

SHEARING MACHINERY.

1,334,391.

Specification of Letters Patent. Patented Mar. 23, 1920.

Application filed February 26, 1919. Serial No. 279,285.

To all whom it may concern:

Be it known that I, HJALMAR NILSSON, a citizen of the United States, residing at Hammond, in the county of Lake and State 5 of Indiana, have invented certain new and useful Improvements in Shearing Machinery, of which the following is a specification, reference being had therein to the accompanying drawings.

10 This invention relates to shearing machinery, and more particularly to what is commonly known as plate shears.

The object of the invention is an improvement in the construction of the ordinary plate shears or shearing machines of 15 the class hereinafter described, whereby an efficient and durable machine is produced at a minimum cost.

Another object of the invention is to produce a machine wherein the main bearings 20 support the main shaft without involving an overhanging or bending strain on the shaft of the machine.

With these and other objects in view, my 25 invention comprises certain novel combinations and arrangements of parts as will be hereinafter specifically described, illustrated in the accompanying drawings, and more particularly pointed out in the appended 30 claims.

In the drawings:

Figure 1 is a view in front elevation of a machine constructed in accordance with the present invention.

35 Fig. 2 is a view in side elevation of my machine.

Fig. 3 is a sectional view taken on line 3—3, Fig. 1.

Fig. 4 is a fragmentary top plan view of 40 the machine shown in Fig. 1.

Fig. 5 is an enlarged view, in elevation, of one of the balance weight devices.

Fig. 6 is a sectional view taken on line 45 6—6, Fig. 1, while Fig. 7 is a front view of Fig. 6.

Fig. 8 is a sectional view taken on line 8—8, Fig. 1.

Fig. 9 is a sectional view taken on line 9—9, Fig. 4.

50 Fig. 10 is a perspective view of the primary jaw, partly shown in section.

Referring to the drawings by numerals, 1 designates the main frame or casting which is provided with a hollow elongated 55 body 2 (Fig. 3), and above the elongated or central body 2 are vertical bearing stand-

ards 3, in which standards 3 is suitably journaled the driving shaft 4.

The primary jaw 5 is supported upon frame 1, and said jaw 5 comprises the hollow end frames 5^a, together with blade 9; each frame 5^a is provided with transversely-aligned elongated slots 7, through which bolts 6 extend, which bolts 6 fasten the frames 5^a in adjusted positions upon the main frame 1. Each frame is provided at its front edge with a flange 5^c, upon which rests the lower edge of the blade 9 (Fig. 10); the blade 9 is of the same width as the flange 5^c, and fastening means, as screws 5^b, 70 secure the ends of the blade to the frames 5^c. Bolts 8 are mounted upon the right-angled extensions 1^a of the frame 1, and these bolts serve to "push" or adjust the jaw 5 transversely of the frame, by the bolts 75 8 bearing against the outer faces of the frames 5^a, so that the blade 9 can be adjusted to a nicety with reference to the blade 9^a of the auxiliary jaw or ram.

The ram 10 is secured in place by the detachable plates 11, which plates 11 are fastened upon the front of the central body portion 2 by means of bolts 12; the ram or auxiliary jaw 10 slides behind these plates 11, and on the ram or auxiliary jaw 10 is 85 a blade 9^a that co-operates with blade 9 for shearing or cutting a sheet or bar of metal. The ram or jaw 10 is provided with extensions 13 in the standards 3, and in these extensions 13 are rotatably mounted the eccen- 90 trics 14.

Loosely mounted upon the shaft 4 is a large gear wheel 15 that is driven or rotated preferably by motor 16; the gear wheel 15 is provided with a clutch member 95 17, and a movable clutch member 18 is keyed upon shaft 4 and when the movable clutch member 18 meshes with the fixed clutch member 17, the motor driving the gear wheel 15 will impart a rotary motion to 100 the shaft 4 and hence a reciprocal movement through eccentrics 14 will be imparted to the auxiliary jaw for producing the shearing or cutting action of the knives.

To operate the clutch, pedal 19 is mounted through links 20, at 21, upon the frame 1, and connected to one of the links at 22, Fig. 1, is a vertical link 23, which link 23 is pivotally connected to lever link 24; the lever link 24 is pivotally mounted on lug 25, 110 and the inner end of the lever link 24 is pivotally connected to a vertically-movable

pin 26, which pin 26 is adapted to engage at its inner end the movable clutch member 18 for operating the same. When the operator desires the keyed clutch member 18 to engage the clutch member 17 on the gear wheel 15, he presses down on the pedal 19, resulting in the pin 26 being raised sufficiently to allow the lever link 27, pivoted at 28 upon the movable clutch member 18, to throw the clutch member into mesh with clutch member 17 through the action of the spring 29 attached to the lower end of link 27. Upon the operator releasing pedal 19, through the action of a spring in the housing 30, partly containing the pin 26, the pin 26 will be forced downwardly causing this lower end to engage the clutch member 18, and as the clutch member revolves, its cam surface 31 will be engaged by the lower end 20 of pin 26, resulting in the end riding over the cam surface and causing the movable clutch member to be disengaged from the clutch member 17, thereby stopping the rotary movement of shaft 4.

25 Each of the balance weight devices comprises a bracket 32 secured to the top of the central body portion 2 and pivotally mounted upon this bracket 32 is an arm 33; upon the outer end of the arm 33 is a large weight 34, and the inner end of the arm 33 is provided with an enlarged apertured portion 35, through which apertured portion extends a pin 36 and mounted on the ends of this pin are links 37, and these links 37 are also 35 mounted upon a sliding block 38, which block 38 is mounted upon bolt 39; bolt 39 is provided with a nut 40, and between the block 38 and nut 40 is positioned coil spring 41. The bolt 39 is provided with a lower 40 sleeve-like end 42, similar in construction to hollow or sleeve-like lugs 43, which lugs 43 are integral with the upper part of the jaw 10; a pin or bolt 44 extends through the lugs 43 and sleeve 42, holding the bolt 39 in 45 position. The spring 41 relieves any jar or shock by a sudden movement of the auxiliary jaw.

In Fig. 6, I have shown in detail one of the pins 45, each of which pins 45 is inserted through a connecting extension 13, and is threaded into the upper part of the ram 10 (Figs. 6 and 7).

50 In Figs. 8 and 9, I have shown an oiler ring 46, fitting around shaft 4 at each of the bearing standards 3. Each standard 3 is provided with an enlarged annular groove 47, which groove is provided with an enlarged or outwardly-flared part 48 at its bottom, constituting a reservoir for a lubricant, in which part 48 the ring 46 is freely mounted. By reason of this ring oiler or oiler ring, the bearings are efficiently 55 lubricated.

60 What I claim is:

65 1. In a machine of the class described, the

combination with a frame, of a primary jaw mounted upon said frame, said jaw comprising hollow ends, said ends provided with elongated slots, fastening means in said slots and adjustably securing the jaw to the 70 frame, horizontally-positioned bolts on said frame for adjusting the jaw in one direction upon the frame, an auxiliary jaw co-operating with said primary jaw, said jaws provided with blades, and means for moving 75 the auxiliary jaw with respect to the primary jaw.

2. In a machine of the class described, the combination with a frame, of a primary jaw on said frame, an auxiliary, movable jaw 80 carried by the frame, a pair of lugs secured to the auxiliary jaw, a bolt secured between said lugs, a block on said bolt, a nut on said bolt, a spring positioned between the block and nut, links connected to said block, a 85 weighted arm pivotally mounted upon the frame, means connecting said arm to the links, and means for moving said auxiliary jaw upon the frame.

3. In a machine of the class described, the combination with a frame, of a primary and an auxiliary jaw carried by said frame, a shaft journaled upon said frame, means connecting said shaft to the auxiliary jaw, a gear wheel loosely mounted upon said shaft, 95 said gear wheel provided with a clutch member, a slideable clutch member keyed upon said shaft and co-operating with the clutch member of the gear wheel, said slideable clutch member provided with a cam surface, 100 a lever link mounted upon the frame and pivotally connected to the slideable clutch member, a spring connected to said lever link, a casing provided with a sliding pin mounted upon the frame, a spring in said casing and exerting a downward pressure upon the pin, the pin normally engaging the cam face of the slideable clutch member for holding the clutch member in an inoperative position, and manually-operated means connected to the pin for holding it in an unset 105 position and releasing the slideable clutch member for engagement with the clutch member of the gear wheel.

4. In a shearing machine, the combination 115 with a primary frame, of a primary jaw mounted upon said frame, said jaw comprising hollow frames provided with flanges, a blade resting upon said flanges, means fastening the blade to the hollow frames, means 120 carried by the hollow frames and said primary frame and being capable of adjusting the jaw upon the primary frame and secure the same in an adjusted position, an auxiliary jaw carried by the primary frame and co-operating with said primary jaw, and means for moving the auxiliary jaw with 125 respect to the primary jaw.

5. In a shearing machine, the combination 130 with a primary frame, of a primary jaw

adjustably mounted upon said primary frame, said jaw including a blade and frames at the end of said blade, means carried by the primary frame and the frames of the 5 jaw for securing the same in adjusted positions transversely of the primary frame, means carried by the primary frame and co-operating with the jaw for adjusting the jaw transversely of the primary frame, and 10 an auxiliary jaw carried by the frame and co-operating with the primary jaw.

6. In a shearing machine, the combination with a primary frame, of a primary jaw slidably mounted upon said frame, said jaw comprising a pair of hollow frames having 15 transversely-alined, elongated slots formed in their bottoms, a blade secured to the inner faces of said hollow frames, means extending through elongated slots and portions of the primary frame for securing the 20 hollow frames and blade in an adjusted position, means carried by the primary frame

and bearing against the outer faces of the hollow frames for adjusting the same transversely of the primary frame, and an auxiliary jaw co-operating with the primary jaw. 25

7. In a shearing machine, the combination with a primary frame, of a primary jaw adjustably mounted upon said primary frame, said jaw comprising a pair of hollow 30 frames each having open ends, each hollow frame provided with alined slots in its bottom, a blade secured to the inner faces of said hollow frames, means extending through the slots of the hollow frames and 35 portions of the primary frame for securing the primary jaw in an adjusted position, means on the primary frame and engaging the hollow frames for adjusting the primary 40 jaw upon the primary frame, and an auxiliary jaw co-operating with the primary jaw.

In testimony whereof I hereunto affix my signature.

HJALMAR NILSSON.
